UNITED STATES PATENT OFFICE.

JOHN F. HEMENWAY, OF NEW YORK, N. Y.

CLOTHES-WRINGER.

1,220,120.

Specification of Letters Patent. Patented Mar. 20, 1917.

Application filed October 2, 1916. Serial No. 123,379.

To all whom it may concern:

Be it known that I, JOHN F. HEMENWAY, a citizen of the United States, residing at New York city, in the county of New York and State of New York, have invented certain new and useful Improvements in Clothes-Wringers, of which the following is a specification, reference being had thereto to the accompanying drawing.

10 This invention relates to certain new and useful improvements in clothes wringers, and more particularly to that class of clothes wringers having a pressure roll releasing mechanism in which the movably mounted top bar is released to allow the same to move vertically to release the pressure on the pressure rolls, the object being to provide a novel form of stop for limiting the upward movement of the top bar so as to prevent the same

15 from becoming detached from the wringer frame.

20 Another object of my invention is to provide a stop which is exceedingly simple and cheap in construction, and one which can be moved into such position that the top bar can be lifted out of the wringer frame so that the pressure means and pressure rolls can be removed when it is desired to repair the same for any cause.

25 Other and further objects and advantages of the invention will be hereinafter set forth and the novel features thereof defined by the appended claims.

In the accompanying drawings,

30 Figure 1 is a side elevation of a clothes wringer showing the application of my improved construction of stop thereto;

35 Fig. 2 is a detail vertical section through the end portion of the movably mounted top bar and keeper carried by the side bar showing the stop in position to limit the upward movement of the top bar;

40 Fig. 3 is a perspective view of my improved construction of stop detached, and

45 Fig. 4 is a detail perspective view of a slightly modified form of stop detached.

Like numerals of reference refer to like parts in the several figures of the drawing.

In the drawing I have shown a clothes wringer of the ordinary construction, comprising a frame 1 having the usual slotted side bars in which are mounted the bearings for superposed pressure rolls, said bearings being engaged by pressure means 2 which is adjusted by pressure screws 3 carried by a movably mounted top bar 4, the pressure

screws being preferably mounted in threaded boxes 5 embedded within the under face of the movably mounted top bar 4 as clearly shown.

60 The movably mounted top bar 4 is held in position within the wringer frame by pivoted latches 6 so that the desired pressure upon the pressure rolls can be obtained, and the latches 6 are actuated by releasing mechanisms 7 on the vertical movement of the pressure rolls, the specific construction of releasing mechanism being shown in my companion case and is herein shown only to illustrate means for holding the top bar in position within the wringer frame, and I do not wish to limit myself to any particular means for holding the top bar in predetermined position which is capable of being manually or automatically released.

65 The threaded boxes 5 of the movably mounted top bar 4 are provided with lateral extensions 8 having spaced slots 9, the intermediate bar thereof forming a pivot 10 on which is pivotally mounted a stop member 11 preferably formed of a strip of metal having one end portion bent around the pivot 10 to form an eye. The ends of the movably mounted top bar are provided with recesses 13 into which the pivoted stop members 11 can be forced so that the top bar will be free to move vertically within the wringer frame in order to enable the same to be detached so that the working parts of the wringer can be readily removed.

70 75 In the construction of wringer herein shown when the pivoted latches are moved out of the path of travel of the movably mounted top bar, the expansion of the pressure means forces the top bar upwardly, and my invention consists in providing novel means for limiting the upward movement of the top bar so as to prevent the same from becoming detached from the wringer frame when the pressure is released.

80 85 90 Secured to the upper end of each of the side bars of the wringer frame 1 is a plate 14 which is provided with a slot 15 into which the stop 11 is adapted to extend so that the upper end of the slot will be engaged by the stop 11 on the upward movement of the top bar in order to prevent the top bar from becoming detached from the wringer frame when the pressure is released.

95 100 105 110 In the modification shown in Fig. 4, the threaded boxes 16 of the movably mounted top bar of the wringer is provided with a lat-

eral bifurcated extension 17, the end of the furcation being bent to form eyes in which are mounted the laterally projecting pivots of the stops 19 so as to allow the same to swing up into the recess of the top bar. The stop 19 is also provided with a depending lug 20 adapted to engage the extension 17 so as to normally hold the same in a horizontal plane whereby the same will be prevented 5 from swinging downwardly when brought 10 into engagement with the end of the slot of the plate carried by the side bars.

From the foregoing description it will be seen that I have provided a clothes wringer 15 with a movably mounted top bar having means for holding said top bar at each end in predetermined position within the wringer frame and means for limiting the upward movement of said top bar when 20 said holding means has been released which means is so constructed that the same can be swung into vertical position within the recesses of the top bar so as to allow the top bar to move vertically.

25 I claim:

1. A clothes wringer, comprising a frame having pressure rolls and pressure means for said rolls mounted therein, a movably mounted top bar mounted in said frame 30 having means for adjusting said pressure means, releasing means for normally holding said top bar in predetermined position within said frame, members carried by the side bars of said frame and pivoted members carried by the top bar engaging said members for limiting the upward movement of the top bar within said frame.

2. A clothes wringer, comprising a frame having pressure rolls and pressure means 40 for said rolls mounted therein, a top bar having means for adjusting said pressure means, releasing means for normally holding said top bar in predetermined position within said frame, slotted plates carried by 45 the side bars of said frame, and pivoted members carried by the top bar extending into the slots of said plates for limiting the upward movement of said top bar.

3. A clothes wringer, comprising a frame 50 having pressure rolls and pressure means for said rolls mounted therein, a top bar movably mounted in said frame, means for normally holding said top bar in predetermined position therein, automatic means 55 for releasing said means, threaded boxes mounted in said top bar, pressure screws carried by said threaded boxes for adjusting said pressure means, said boxes being provided with extensions, plates carried by 60 the side bars of said frame having slots, and pivoted members mounted on the extensions of said boxes extending into said slots for limiting the upward movement of said top bar when released by said automatic means.

4. A clothes wringer, comprising a frame having pressure rolls and pressure means for said rolls mounted therein, a top bar movably mounted in said frame having means for adjusting said pressure means, 70 said top bar having recesses formed in its ends, means for normally holding said top bar in predetermined position within said frame, means for releasing said top bar, members carried by the side bars of said 75 frame, pivoted members mounted in the recesses of said top bar engaging said members for limiting the upward movement of said top bar within said frame, and means for holding said pivoted members in horizontal position.

5. A clothes wringer comprising a frame having pressure rolls and pressure means for said rolls mounted therein, a top bar movably mounted in said frame having recesses formed in the ends thereof, threaded boxes carried by said top bar, pressure screws mounted on said boxes for adjusting said pressure means, said boxes having portions extending into the recesses of said top 90 bar provided with pivots, plates secured to the side bars of said frame having slots, and members pivotally mounted on the pivots of said boxes extending into the slots of said plates for limiting the upward movement of said top bar.

6. A clothes wringer, comprising a frame having pressure rolls and pressure means for said rolls mounted therein, a top bar movably mounted in said frame having means for adjusting said pressure means, plates secured to the side bars of said frame having slots, members pivotally carried by the top bar extending into said slots for limiting the upward movement of said top 100 bar and means for limiting the swinging movement of said pivoted members.

7. A clothes wringer, comprising a frame having pressure rolls and pressure means for said rolls mounted therein, a top bar 110 movably mounted in said frame having recesses at its ends, slotted plates secured to the side bars of said frame, stops pivotally carried by said top bar, and capable of being moved into the recesses of said top bar, 115 said stops extending into the slots of said plates for limiting the upward movement of said top bar within said frame.

8. A clothes wringer, comprising a frame having pressure rolls and pressure means 120 for said rolls mounted therein, a top bar movably mounted in said frame having pressure screws for adjusting said pressure means, said top bar having recesses at its ends, pivoted stops mounted in said recesses, 125 means for limiting the swinging movement of said stops and slotted plates carried by the side bars of said frame to receive said stops for limiting the upward movement of said top bar within said frame.

9. A clothes wringer, comprising a frame having pressure rolls and pressure means for said rolls mounted therein, a top bar movably mounted in said frame having 5 means for adjusting said pressure means, and pivoted stops carried by the top bar for limiting the upward movement of said top bar within said frame, said stops being capable of being swung into the recess of said 10 top bar for allowing said top bar to move upwardly out of the wringer frame.

10. A clothes wringer, comprising a frame having pressure rolls and pressure means for said rolls mounted therein, a movable 15 member mounted in said frame having means for adjusting said pressure means,

means for normally holding said movable member in predetermined position within said frame, means for releasing said movable member, members fixed to said frame, 20 and pivoted members carried by said movable member engaging the fixed members of said frame on the upward movement thereof for limiting the movement of said movable member within said frame. 25

In testimony whereof I hereunto affix my signature in the presence of two witnesses.

JOHN F. HEMENWAY.
